William M. Green
ATTORNEY.

UNITED STATES PATENT OFFICE.

WILLIAM R. WILEY, OF MOUNT CLEMENS, MICHIGAN.

SNAP FASTENER.

Application filed June 18, 1923. Serial No. 645,987.

To all whom it may concern:

Be it known that I, WILLIAM R. WILEY, a citizen of the United States, residing at R. F. D. No. 4, Mount Clemens, county of Macomb, State of Michigan, have invented a certain new and useful Improvement in Snap Fasteners, and declare the following to be a full, clear, and exact description of the same, such as will enable others skilled in the art

10 to which it pertains to make and use the same, reference being had to the accompanying drawings, which form a part of this specification.

This invention relates to snap devices for 15 automobile curtains and the like, and has for its object an improved organization of parts which combines unusual cheapness of manufacture with efficient uniting action, except when the parts are intentionally actuated in 20 just the relative direction intended, when their separation may be easily effected.

In the drawings:

Figures 1, 2 and 3 are views of the principal component parts of my improved construction.

Figure 4 is a large scale diagrammatic view of the parts of the snap catch in assembled form and with the unlocking positions of the parts shown in Figures 2 and 3 indicated 30 in dotted lines.

Figure 5 is a sectional elevational view taken along the line 5—5 of Figure 4.

Figure 6 is a shaded perspective, differing only slightly from Figure 4, designed to emphasize the relative positioning of the mushroomed edge of the head shown in Figure 2 and of the overturned edges of the stamping shown alone in Figure 3.

Figure 7 is a partly sectional elevational 40 view of a pair of curtains carrying the snap button parts, showing an intermediate step in the attaching or detaching operation.

At B in Figure 1 is shown a form of disc or washer provided with a central upstanding stud C, which latter is adapted to engage through the aperture A' in the mushroomed head A to secure the same on one surface of a fabric curtain, such as are commonly used for motor vehicle tops. If the mushroomed head A is designed to be positioned 50 on a solid portion of the vehicle body, it may be held in place by means of a nail or screw passing through its aperture A'. Such a disc or washer as B is similarly used to hold 55 the stamping E, shown in Figure 3, in position on a second curtain section, whose de-

tachable association with the curtain piece carrying the mushroomed head A may be desired, the edges of the disc B making it easy of seizure with one's fingers to start the detaching movement of the two parts. The mushroomed head A and stamping E thus supported on their respective curtain sections constitute the main cooperating parts which this disclosure concerns.

As brought out in Figures 3 and 4 the stamping E is in superficial extent perhaps one-third or a quarter short of being a complete circle, and its peripheral edges adjacent to the straight edge or squared side F are provided with underrun points or inward projections G, which are adapted to engage positively under the peripheral edge H of the stud A, as is also the indent point J which is located on the peripheral curved edge of the stamping E opposite this straight edge F. The fit of these points under the mushroomed edge H is so accurate that a straight pull, such as would be exerted by the wind upon the curtains which are thus connected, would ordinarily fail of separating effect. If it is drawn down slightly, that is, in a plane parallel with that of the disc B to the dotted line position Z shown in Figure 4, the lower edge of the stamping, carrying the indent point J can then be swung away from the disc B, about the straight line joining the points G as an axis until the point J is clear of the mushroomed edge H as shown in Figure 7, after which a slight lifting movement of that part of the curtain which carries the stamping will suffice to clear the points G from the mushroomed edge H. Similarly, to lock the parts in place, the points G and the straight edge F are first slipped under the mushroomed edge H, and the stamping E as a whole then moved downwardly slightly relative to the plane of the disc B, until the underrun point J engages under the mushroomed edge H to a degree of interlocking similar to that of the points G.

What I claim is:

1. A snap catch, having, in combination with a mushroomed head, an overengaging snap shell therefor, consisting of an apertured stamping having a straight edge on one side and an otherwise circular underrun edge constituting the remainder of its periphery, the points of union of the two portions of the edge of the stamping being formed as locking points for engagement

under the edge of the mushroomed head, and that portion of the curved periphery of the stamping lying opposite its straight edge being provided with a similar locking point, 5 said snap shell being adapted to be detached from engagement with said mushroomed head by being swung about the line joining said first named locking points as a center and being moved through a plane parallel 10 with that of the mushroomed head.

2. The combination, with a mushroomed head having an undeturned peripheral edge, of a centrally apertured stamping having a straight edge constituting a part of its other- 15 wise circular periphery, and a plurality of undeturned points located at the ends of said straight-edged portion and at that portion of the curved periphery substantially opposite thereto, said stamping being adapt- 20 ed to be moved through a plane substantially parallel to that of the mushroomed head and thereafter swung to an oblique position with respect thereto about a line passing through the first named pair of points as an axis, to 25 effect disengagement of the third tongue on the stamping from the undeturned edge of the mushroomed head.

3. In combination, with a generally convex head member having slightly under- 30 turned edges, a centrally apertured shell having a concave exposed face the edge portions of which are provided with a plurality of inwardly projecting bearing points, two of which are adapted to serve as bearing points 35 about whose axial line the shell is adapted to be rocked and moved in a plane substan-

tially parallel to that of the shell as a whole, to effect the locking engagement of the oppositely disposed other bearing point under an oppositely disposed portion of the edge 40 of the convex head member.

4. In a combination with an entering member provided with an undeturned peripheral edge, a complementary receiving shell whose curved outwardly-turned edges 45 are adapted to engage over said undeturned peripheral edge of the entering member at a plurality of indented points thereon, two of said points being located at the ends of a straight-edged cut away portion, about which 50 as an axis the remaining portion of the shell is adapted to be slightly rocked to effect the engagement and disengagement of the oppositely positioned other bearing point.

5. A snap fastener, having in combination 55 a mushroomed head piece, and a centrally anchored shell piece adapted to have oppositely disposed bearing points on its outwardly turned peripheral edge brought into anchoring engagement about the edge of said mushroomed head, two of said bearing points 60 serving as the termini of an axis about which the body of said shell piece is rocked to effect the engagement or disengagement of the third bearing point with respect to the edge 65 of the mushroomed head.

In testimony whereof, I sign this specification in the presence of two witnesses.

WILLIAM R. WILEY.
